STOVE

Frederick E. Hughes, Port Loring, Ontario,
Canada

Application October 14, 1935, Serial No. 44,842

3 Claims. (Cl. 126—190)

The principal object of this invention is to provide an improved fire door structure for stoves which will greatly facilitate the replenishing of the fire and will eliminate to a great extent the danger incident to the release of flying sparks or coals when refueling.

A further object is to obviate the danger of flaring gases and the discharge of smoke and fumes into the room on the opening of the fire door.

The principal features of the invention reside in the novel construction and arrangement of the stove structure whereby the refueling door, which is of substantially trough shape, extends the full width of the fire box from side-to-side of the stove to receive a length of cord wood or other fuel in its open position and to automatically deposit the same within the combustion chamber or fire box on the closing of the door and this door is connected with means for opening the flue to create a direct draft when the door is opened.

The invention further resides in the novel formation and manner of mounting the door in conjunction with the adjacent lower portion of the stove front whereby a smooth unobstructed path is provided for the passage of the fuel from the door into the combustion chamber.

Figure 1 is a fragmentary mid-sectional side elevational view of a stove constructed in accordance with the present invention.

Figure 2 is a side elevational view of the construction shown in Figure 1.

Figure 3 is a front elevational view of the upper fire door portion of the stove showing the door closed in one half of the drawing and open in the other half.

Figure 4 is a fragmentary sectional plan on the line 4—4 of Figure 1 indicating in chain lines 40 the open position of the door.

Figure 5 is a fragmentary perspective view of a modified form of the invention in which the fire door is operatively connected with the flue damper.

Figure 6 is an enlarged elevational view of the damper control device.

In the form of the construction shown the sides 1 and 2 of the stove, which may be of sheet metal, are stepped forwardly at the point 3 intermediate of the height and the forward upper portion is rounded outwardly in a convex formation 4.

A casting 5 of stepped formation is fitted between the stepped portions of the side panels 1 and 2 and is provided with a thickened portion

6 below the fire door opening 7, the inner surface of the portion 6 being sloped downwardly and inwardly to meet the side 6' of the fire box and forming with the surface of the portion 6', a chute which slopes continuously downward forming an unobstructed passage from the door to the interior of the firebox so that when the door with its charge of fuel is closed there will be no possibility of the fuel becoming lodged and complete discharge thereof into the firebox will be ensured.

A fire door 3 is fitted between the upper edge of the portion 6 and the top 9 of the stove and is of substantially trough-shaped formation presenting a concaved inner side 10 which forms 15 a continuation of the sloping inward surface of the portion 6 of the front casting 5. The door 10 is stepped upwardly along the bottom edge at 11 on the outward side forming a downwardly extending part-cylindrical flange on the inward side, the rounded contour of which rests in the grooved upper portion of the section 6 to form a closure from side-to-side of the door opening, while at the same time permitting the free swinging movement of the door.

The rounded flange portion of the door is extended outwardly at either end beyond the side panels 1 and 2 of the stove and preferably journaled in upstanding lug portions 12 of the casting 5 and the end extremities are provided with bell cranks 13 which are engaged by springs 14 suitably anchored at 15 to the side panels so that the springs co-operate with the cranks to hold the door in either open or closed positions.

End flanges 14' are carried on the concaved side of the door and these fit snugly adjacent the inner surfaces of the side panels 1 and 2 to form a substantial closure thereagainst, and they also serve to hold the fuel that is placed within the trough formation of the door when the latter is in open position as indicated in chain lines 35 Figure 1. They are also formed with stop lugs X sliding in the arc-shaped grooves X' which hold the door in a horizontal position when open.

When the door is swung outwardly and downwardly to the open position as indicated in Figure 1, a length of cord wood or other fuel may be placed on the door, the opening movement of the door being limited by reason of the engagement of the stop X with the upper and outer end 50 of the groove X'. The door presents a smooth inner surface continuous with the inner surface of the section 6 of the casting, so that when it is tilted upwardly the fuel will slide or roll inwardly without meeting any obstruction and it 55

will continue down over the inward and downward sloping surface of the portion 6 to be deposited completely within the fire box. Any sparks that will be thrown upwardly will be prevented from escaping by reason of the simultaneous closing of the door, and since the door extends completely across the full width of the fire box, an even distribution of the fuel from end to end of the fire box will be achieved and it is important to note that cordwood of full firebox length may be supplied to the firebox in this way, whereas in present stove constructions when refueling through the front, it is necessary to cut the cordwood in lengths considerably shorter than the firebox or else insert the longer length of wood through an end door or through the top of the stove, which practice is objectionable and dangerous due to the release of smoke, gases and sparks each time the fuel is replenished.

In the form of the invention shown in Figure 5 a crank member 16 is secured to an axial extension 16' of the door 8' adjacent to the back of the stove and is connected by a rod 17 to a rocker member 18 mounted on a pivot pin 19 arranged at a suitable place on the back of the stove and this rocker member is arranged to engage a pin 20 on a lever 21 also pivoted on the pin 19. The lever 21 is connected by a rod 22 to the cranked end of a damper 23 in the smoke flue. When the door 8 is opened the rocker member is operated to open the damper so that gases within the stove will be immediately liberated through the flue preventing the flashing or puffing of smoke into the room where the stove is located.

The lever 21 is provided with an arm 24 by means of which the damper may be operated from the side of the stove independent of the door 8, the lever 21 moving independently of the rocker member 18.

A door 25 is mounted in the opening of the ash pit 26 beneath the grate and extends the full width between the side walls 2, the rounded bottom edge 27 of said door being rotatably supported in a groove 28 in the frame. This door is provided with side wings 29 which fit snugly

against the sides 2 of the stove and form dust-tight joints.

What I claim as my invention is:—

1. In a stove of the front refueling type in which a refueling door is hinged to swing upwardly to discharge a quantity of fuel through the door opening into the interior of the stove, in combination therewith means forming a chute sloping continuously downward from the hinge side of the door directly into the firebox forming a non-obstructed passage from the door to the combustion zone of the firebox whereby lodgement of the fuel between the door and firebox is prevented, said chute-forming means including a front portion presenting an inner surface which forms a smooth unbroken surface continuation of the inner surface of the door when the latter is in its closed position.

2. Means as claimed in claim 1 in which the inner surface of said front portion slopes steeply upward to a horizontal hinge recess in which the hinge side of the door is rotatably sealed, the rotatably sealed hinge portion of the door being surfaced on the inward side in continuation of the door surface and forming a flush steeply sloped continuation of the steeply sloped surface of said front portion when the door is moved to the closed position.

3. A stove of the front refueling type having in combination with the firebox, a front refueling fire door opening extending the full length of said firebox from side-to-side of the stove, and a chute portion sloping directly and unobstructedly into said firebox, a horizontally hinged refueling fire door also extending the full length of said firebox, and means for maintaining a flush seal between the hinged side of said door and the inner top extremity of said chute from end to end thereof substantially unaffected by the opening and closing of the door to permit charging of fuel completely and unobstructedly from the door into the firebox and prevent dust or sparks from passing between the hinge side of the door and the chute.

FREDERICK E. HUGHES. 45
